UNITED STATES PATENT OFFICE.

RICHARD BECKMAN AND HERMANN WOLLESEN, OF NEW YORK, N. Y.

EXPLOSIVE-MOTOR.

1,301,359.

Specification of Letters Patent. Patented Apr. 22, 1919.

Application filed March 27, 1918. Serial No. 224,976.

To all whom it may concern:

Be it known that we, RICHARD BECKMAN and HERMANN WOLLESEN, subject of the German Emperor, and citizen of the United States of America, respectively, residing in the borough of Manhattan, city, county, and State of New York, have invented certain new and useful Improvements in Explosive-Motors, of which the following is a specification.

The invention relates to explosive motors of the rotary type, by which term is meant to include an engine having a series of reciprocating pistons moving back and forth in corresponding cylinders, while the cylinders and the frame on which they are mounted rotate about a fixed crank shaft.

The purpose of the invention is to improve the construction and operation of such a rotary type engine by the provision of novel fuel-feeding devices, with a view to increasing the power of the motor and also lessening its cost of operation, by obtaining a maximum power from the fuel consumed per unit of time. More specifically, the invention resides in feeding fuel to the outer ends of the cylinders through inlet valves located at the outer ends of the cylinders. This is accomplished in a general way by connecting each cylinder, during a portion of its revolution, with a fuel chamber from which the cylinder is supplied. As the fuel chamber is independent of and entirely removed from the crank case or crank shaft, it is possible to secure a uniform mixture of fuel in its state of original purity.

By having the fuel inlet valves located in the outer ends or heads of the cylinders, the structure is rendered practicable for aeroplane application, in which cylinders must be made from forgings throughout, so as to obtain the necessary strength and equilibrium.

In the present structure, the intake chamber is separated from the exhaust so that the danger of backfire is eliminated, the exhaust taking place during a different portion of the cylinder's revolution from that of the fuel-feeding operation.

One method of carrying out the invention involves utilizing a stationary segmental channel section which co-operates with a movable channel ring or section that travels with the cylinders. The channel ring is of circular form and in communication with

each cylinder at the outer end of the latter, and the portion of the channel ring positioned adjacent to the stationary channel section at any given moment, forms therewith the fuel chamber, and serves to admit fuel to such cylinders as have their valves in the open position and are in communication with the fuel chamber.

To these and other ends the invention consists in certain improvements and combinations of parts as will be hereinafter more fully described and pointed out in the claims following the specification.

In the drawings—

Figure 1 is a vertical sectional view, partly in diagram, showing the invention as applied to a rotary type motor;

Fig. 2 is an enlarged view of the valve-operating means;

Fig. 3 is a cross-sectional view of the fuel chamber;

Fig. 4 is a detailed side elevation of the fuel chamber, partly broken away;

Fig. 5 is a transverse sectional view, taken centrally of the motor;

Fig. 6 is a diagrammatic view showing the position of a cylinder and valve at the beginning of a complete cycle, or at the start of the fuel-feeding stage;

Fig. 7 is a similar diagrammatic view, showing the position of the cylinder and valve at the completion of the fuel-feeding stage and the beginning of the fuel compression;

Fig. 8 is a similar view, showing the position of the parts as the explosion takes place, and

Fig. 9 is a similar view showing the relative positions of a cylinder and valve after the explosion has occurred and at the commencement of the exhausting operation.

The novel and underlying features of the improvement may be carried out in a variety of ways and for the purpose of illustrating one possible embodiment, the disclosure comprises a frame A which supports a series of cylinders B. The several cylinders B and the frame A rotate about a common center or fixed crank shaft C. The latter has a common crank C' connected to each one and the pistons B' by means of a connecting rod B².

Each cylinder is provided at its outer end or head with a port B³ controlled by a valve B⁴. The latter is mounted on a valve stem B⁵ and is operated for opening and closing

in a manner that will be described presently.

The frame A and cylinders B have connected thereto a circular channel section E which rotates with the cylinders and is connected with the ports B³ by means of communicating conduits E'. The channel E is continuous and uninterrupted and during a part of its rotation co-operates with a stationary complementary channel section which is in communication with a fuel supply and forms with the moving channel, a fuel chamber.

To this end we employ the stationary segmental channel section F shown in Figs. 1 and 3. The channel section F is closed at its ends by the walls F' and is connected with a carburetor or fuel supply by means of a pipe F². The channel section F, which is stationary, is preferably provided with thin plates K in the form of extensions or flanges which are attached by means of screws F³ and engage corresponding grooves E² in the channel section E. This affords an effective sealing means between the channels so as to constitute a closed fuel chamber between the end walls F' of the stationary section.

Assuming the cylinders and frame to be traveling in an anti-clockwise direction, as shown in Fig. 1, at the beginning of a cycle, the inlet valve is opened as the cylinder reaches the top position. As it travels downwardly to the left and comes in communication with the fuel chamber, fuel is taken in while at the same time the piston travels inwardly and causes a suction. As the cylinder reaches the end of the fuel chamber, its valve is automatically closed, as shown in Fig. 7, and compression takes place by the outward movement of the piston during the outward travel of the cylinder. When the latter again reaches its uppermost position, as shown in Fig. 8, the explosion takes place, forcing the piston inwardly and causing the cylinder to travel from the position in Fig. 8 to that of Fig. 9. During this last mentioned movement, which comprises the first half of the second revolution of one cycle, the valve remains closed until it reaches the position of Fig. 9. The valve then opens and the burnt gases are exhausted during the upward movement of the cylinder, a cycle being completed at the end of two complete revolutions of a cylinder. The valve-operating means, by which the position of the valves is automatically governed, will now be described.

Mounted upon the fixed crank shaft C is a pinion C² which is also stationary and engages a gear G. The latter is journaled in the cylinder frame A and is geared to the pinion C² in the ratio of two to one so that the gear G will be rotated through one complete revolution only once for every two rev-

olutions of the frame and cylinders. There are a number of gears G, one for each cylinder and valve, and they are mounted upon arbors G² which are also provided with fixed cams G³. The latter engage connecting rods G⁴ which operate the valve levers G⁵. These are pivoted at G⁶ and have end portions G⁷ which contact with the outer ends of the valve stems B⁶. The valves are held normally closed by means of springs B⁸. As the cylinders and frame rotate about the fixed crank shaft, the cams G³ are turned once for every two rotations of the frame and this causes each valve B⁴ to be opened and closed so as to complete the cycle, illustrated in Figs. 6 to 9, inclusive.

It is desirable that the fuel chamber be at no time in direct communication with the atmosphere, and to accomplish this purpose, the end walls F' extend upwardly into substantial contact with the outer wall of the channel section E and their edges extended peripherally to afford surfaces F⁴ which are preferably of at least as great width as the openings E' in the section E. This arrangement prevents the openings E' from being partially in communication with the stationary section F and partially in communication with the atmosphere, and insures their being cut off from atmospheric communication before the inlet chamber is uncovered.

The structure described enables obtaining a constant gas mixture, giving proper combustion on an economical basis. The overhead valve arrangement permits making the cylinders from forgings, resulting in a balanced motor with the equilibrium that is necessary, particularly to aeroplane operation. The gaseous fuel mixture is readily fed at all times in the correct proportions without coming into contact with any of the moving parts of the motor or its lubricating oil, as is the case where the fuel is fed through a chamber surrounding the crank shaft. A further important advantage of the invention resides in separating the intake chamber from the exhaust zone, as this reduces and practically eliminates the possibility of backfire.

The essential features of our improvements are considered to be the supplying of fuel directly to the outer ends of the walls of a rotary type motor from a fuel chamber which is independent of the crank shaft and oil feeding devices, and accomplishing this by periodically bringing each cylinder into communication with a fuel chamber and opening the supply valve at such time. It is not intended to limit the invention to the structure described herein or any close approximation thereof, as the purposes can be equally well accomplished by various modified arrangements of valve-operating means and communicating fuel feed instrumentalities.

ties without departing from the spirit of the invention or the scope of the following claims.

What we claim is:—

1. In an explosive engine, the combination with a plurality of cylinders which are rotatable about a common center, of a fuel chamber comprising a stationary section and a movable section which rotates with said cylinders and has different portions co-operating successively with the stationary section to form a closed chamber, and fluid-conducting means leading from said different portions of the movable section to the various cylinders.
2. In an explosive engine, the combination with a plurality of cylinders which are rotatable about a common center, of a fuel chamber comprising a stationary section and a movable section which rotates with said cylinders and has different portions co-operating successively with the stationary section to form a closed chamber, a valve in the outer end of each cylinder controlling a port, and fluid-conducting means leading from said different portions of the movable section to said ports.
3. In an explosive engine, the combination with a plurality of cylinders which are rotatable about a common center, of a stationary segmental channel section, a channel member movable with the cylinders and having different portions co-operating successively with said channel section to form a fuel chamber, and fluid-conducting means leading from said different portions of the channel member to the several cylinders.
4. In an explosive engine, the combination with a plurality of cylinders which are rotatable about a common center, of a channel ring movable with the cylinders, fluid-conducting means leading from the channel ring to the cylinders, and a stationary channel section co-operating successively with different portions of said channel ring and forming a fuel chamber.
5. In an explosive engine, the combination with a plurality of cylinders which are rotatable about a common center, of a channel ring movable with the cylinders, fluid-conducting means leading from the channel ring to the cylinders, a stationary channel section arranged to form a fuel chamber with part of the channel ring during rotation of the latter, sealing devices between adjacent walls of the channel members, and a closure at each end of the stationary channel section.
6. An explosive motor comprising a plurality of cylinders rotatable about a common axis, a fuel chamber comprising a stationary portion adapted to be connected with a fuel supply and a movable portion carried by said rotatable cylinders and co-operating with the stationary portion to form a chamber which communicates successively with the various cylinders.
7. An explosive motor comprising a plurality of cylinders rotatable about a common axis, a fuel chamber comprising a stationary segmental portion adapted to be connected with a fuel supply and a movable annular portion carried by said rotatable cylinders and having different portions co-operating successively with the stationary segmental portion to form a chamber which communicates successively with the various cylinders.

In witness whereof, we have hereunto signed our names.

RICHARD BECKMAN.
HERMANN WOLLESEN.
